UNITED STATES PATENT OFFICE

GEORGE R. GORHAM, OF CHICAGO, ILLINOIS, ASSIGNOR OF ONE-HALF TO
ABEL R. ANGLE, OF INDIANAPOLIS, INDIANA.

GRAIN-TREATING APPARATUS.

SPECIFICATION forming part of Letters Patent No. 604,880, dated May 31, 1898.

Application filed May 14, 1897. Serial No. 636,530. (No model.)

To all whom it may concern:

Be it known that I, GEORGE R. GORHAM, a citizen of the United States, residing at Chicago, in the county of Cook and State of Illinois, have invented certain new and useful Improvements in Grain-Treating Apparatus, of which the following is a specification.

The proper care of grain in commercial "elevators" is difficult and expensive. The bins are necessarily large and the quantity of grain stored in each correspondingly great, so that, particularly if, as is frequently the case, such grain is somewhat damp when placed in the bins, its tendency is to "heat" and become spoiled. The grain is likewise subject to such "heating" and also "sweating," if stored while somewhat green or in that condition in which grain is which has been threshed before it has undergone the process of sweating while in the straw. To prevent such consequences, constant care and watching and much rehandling have been necessary.

The object of my invention is to provide a means by which grain can be dried and cooled in the bins and without rehandling.

It consists in an apparatus of novel construction and arrangement whereby hot and cold air may be efficiently forced through the grain as may be desired. It is essential in an apparatus of this character that the blast of air should be of great force and that the distribution shall be capable of being easily and accurately controlled. Previous apparatus have been faulty in these particulars and are in many respects widely different from my apparatus, which will be first fully described and the novel features then pointed out in the claims.

Referring to the accompanying drawings, which are made a part hereof, and on which similar letters of reference indicate similar parts, Figure 1 is a view in elevation of the essential portions of my apparatus, illustrating its arrangement and use. Fig. 2 is also an elevation as seen at right angles from the point of view of Fig. 1; Fig. 3, a vertical sectional view through a grain-bin provided with my apparatus and attachments on an enlarged scale, the central portion thereof being broken away; Fig. 4, a horizontal sectional view on

the dotted line 4-4 in Fig. 3, and Figs. 5 and 6 detail views illustrating the valves and immediately adjacent parts employed in such apparatus.

It may be stated generally that this apparatus is designed to be used in connection with large elevators and warehouses wherein a steam plant forms a portion of the equipment. Such a plant includes necessarily one or more boilers A wherein to generate steam for the engine which drives the elevators. (Not shown.) The bins B are in themselves ordinary elevator-bins. These boilers, bins, and the general construction and arrangement of the building may be understood to be such as are in common use.

Running from the boilers or the steam-dome a thereon is a pipe 1, which runs to the steam-cylinder 2 of an air-compressor and conveys steam thereto to actuate the same. From the compressing-cylinder 3 of said air-compressor a pipe 4, having a check-valve *v*, leads to branch pipes 5 and 6. Said pipe 5 runs to a coil of pipes 7, arranged to be heated by the furnace and preferably placed within the brickwork between the boilers A, as shown. From said coil a pipe 8 runs along past the elevator-bins B, and from this pipe 8 branches containing valves 9 run to perforated or reticulated columns 10, standing vertically within the bins. These columns 10 may be supplemented by other columns 11 of a similar character, but preferably smaller in size, distributed at various points throughout the bin and connected with the central column by 85 means of horizontal pipes 12.

A cold-air tank 13 is suitably placed and a pipe 14 connects said tank with the pipe 8, leading from the coils 7. By manipulating the valves 15 and 16 the current of air may be changed to pass through the cold-air tank 13 instead of the heating-coils 7, communication with said heating-coils being cut off by means of said valve 15 and the valve 17 in the pipe 8, which in that event are closed, while the valve 16 is left open. When the hot air is being used, communication with the tank 13 is cut off by closing the valves 16 and 18. Valves 19 are placed in the pipe 8 between each of the bins B, so that the flow of air be- 100

yond any particular bin desired may be cut off, and any particular bin may be cut off altogether by the corresponding valve 9.

The reticulated or perforated columns 10 and 11 are best shown in Figs. 3 and 4, where they are illustrated on an enlarged scale. They are preferably principally composed of fine wire-netting rolled into tubular form and extend from the bottom to near the top of the 10 hoppers, but may be of any desired construction, so that they are provided with perforations through which the air may escape to the grain. These hoppers in actual use are very tall, and consequently in Fig. 3 only 15 the upper and lower ends are shown, by far the greater part of the intermediate portion being broken away. As it is desirable from time to time to utilize my invention in connection with bins of grain only partially 20 filled, it is necessary to shorten the effective portions of these perforated or reticulated columns in accordance with the varying heights of grain in the bins. I therefore provide valves or dampers 20, which may be conveniently operated by rods 21, running to outside the bins. 25 These of course may run in any desired direction, and the valves may be interposed as frequently as is deemed best. These valves may be plain sliding dampers, as illustrated 30 in Fig. 1, or they may be regular gate-valves, as shown in the other figures.

In order to provide for a higher temperature of the air than is likely to be given by simply passing it through the coils 7, I have 35 shown in Fig. 2 an air-heating drum C, similar in form and arrangement to one of the boilers A, but (usually) of less size, although mounted and heated in the same manner. This is coupled to the pipe 1 by means of a 40 pipe 22, and when both the valves 23 and 24 are open air will be driven from the compressor through both the coils 7 and this heating-drum C. When the valve 23 is closed, the air will flow through the heating-drum C alone, 45 and when said valve is open and the valve 24 closed the air will flow through the coils alone. Thus either the coils or the heating-drum may be utilized for heating the air, or both together, as may be desired. The discharge end of the 50 heating-drum C is connected to the pipe 8 by means of a branch pipe 25, in which I prefer also to place a valve 26. The horizontal pipe 27 is practically a continuation of the pipe 5. While I have shown this extra heating-drum 55 C and attachments corresponding therewith, I do not expect that they will usually be necessary. On the contrary, in most cases the heating of the air is accomplished by passing it through the coils 7 and practically without 60 cost, this heating being performed by what

would otherwise be waste heat from the furnace.

Having thus fully described my said invention, what I claim as new, and desire to secure by Letters Patent, is—

1. The combination, in a grain-treating apparatus, of the furnace and boilers, an air-compressor driven from said boilers, coils of pipe arranged within said furnace, a heating-drum arranged adjacent thereto and heated therefrom, a pipe running from said air-compressor and connected both with said coils and with said drum, a pipe connected both with said coils and said drum and running past the grain-bins, said grain-bins, perforated columns therein, said pipe being connected by branches to said columns, and valves arranged in the various pipes, whereby the air may be directed through one or both of said heating devices, and any or all of said bins, substantially as set forth. 75

2. The combination, in a grain-treating apparatus, of the bins, vertical perforated columns within the bins, valves interposed in said columns at intervals whereby the effective height thereof can be varied, air-pipes connected to the bottom of said columns, and an air-compressor for supplying air to said pipes, said several parts being arranged and operating substantially as shown and described. 85

3. The combination, in a grain-treating apparatus, of a furnace and boiler, an air-compressor driven therefrom, heating-coils arranged within the structure of said furnace, a cold-air reservoir suitably located, a pipe 95 leading from the compressing-cylinder of said air-compressor having branches which lead to said coils and to said reservoir, valves whereby the flow of air can be caused to travel in either direction from said air-compressor, pipes leading from said coils and said air-reservoir to a common point where they unite, a continuation of one of said pipes past grain-bins, said grain-bins, perforated columns extending vertically up in said grain-bins, connections between said pipe and said columns, and suitable valves interposed in said several pipes, whereby the flow of air can be controlled, and whereby either cold or hot air can be driven by means of said air-compressor into said perforated columns and thus through the grain in said bins, substantially as and for the purposes set forth. 105

In witness whereof I have hereunto set my hand and seal, at Indianapolis, Indiana, this 115 8th day of May, A. D. 1897.

GEORGE R. GORHAM. [L. S.]
